CARBON PACK FOR CONTINUOUS-FORM
STATIONERY

Lester K. Fleischmann, Chicago, Ill.

Application May 29, 1951, Serial No. 228,898

2 Claims. (Cl. 282—1)

1

This invention relates to carbon packs for use between strips of continuous-form stationery in a writing machine, and more particularly to an improved way of securing carbon sheets to a leader sheet.

The present invention is an improvement on the device shown in my Patent No. 2,233,204, issued February 25, 1941. The patented device has been in wide use for many years, but as the carbon strip was folded along the line of stitching, when in writing position, it was sometimes accidentally torn from the leader sheet. This difficulty has been overcome by sewing the rear end of the sheets to the underside of the leader sheet, so that in extended position tension is applied directly to the line of stitching, and the strength of the connection is approximately doubled.

The invention is illustrated in a preferred embodiment in the accompanying drawings, in which—

Fig. 1 is a perspective view showing the carbon pack before it is folded back into its normal position; Fig. 2, a perspective view showing the pack ready for use, and how it is anchored on the carbon blade of a writing machine; Fig. 3, an enlarged fragmentary sectional view, taken as indicated at line 3—3 of Fig. 1; and Fig. 4, an enlarged fragmentary sectional view, taken as indicated at line 4—4 of Fig. 2.

In the embodiment illustrated, it will be understood that the thickness of the sheets has been grossly exaggerated for clearness. Actually, a full carbon pack will fit between a pair of forwardly advancing stationery strips without producing any series bulkiness.

In the embodiment illustrated, a leader sheet 5 is folded, as indicated at 6, so that it may be slipped over and anchored by a conventional carbon blade 7 which is part of a typewriting or billing machine.

A desired number of carbon sheets 8 are brought into superposed relation with their carbonized rear-end portions facing upwardly against the underside of the leader sheet 5. The rear portions of the carbon sheets near the front portion of the leader sheet are then fastened together, preferably by a straight line of stitching 9, which may be in the form of a chain stitch.

The carbon sheets are then folded rearwardly around the front end of the leader sheet, as indicated at 10. The carbon sheets are then folded forwardly within the leader sheet, as indicated at 11. In the form illustrated, the carbon sheets are folded upwardly together, but if preferred their free end portions may be folded downwardly to a position against the forwardly extending portion of the leader sheet.

It will be understood that the outer carbon sheet may be completely unfolded to extended position from the leader sheet, so that it will ex-

10 tend forwardly for manifolding use between stationery strips. In that position, the working carbon sheet is held directly by the straight line of stitching and does not have a fold through which any pulling stress must be transmitted. This arrangement provides a very strong connection and will withstand a substantial pulling stress. However, when a carbon sheet has been sufficiently worn it may be torn off readily by

15 a downward or angular pull from the stitching.

The present carbon packs are well adapted for use with separate strips of stationery or fanfold stationery. However, with fanfold stationery it is usually desirable to notch or trim off the corners of the pack. If desired, the carbon sheets may be inclined a few degrees from the leader sheet, so that the free end of the working carbon strip will be directed well into the lateral fold of the fanfold stationery. In any case, the present construction provides better alignment of the carbon sheets with respect to the leader sheet, because it does not have to pull through a fold or around the stubs of previously used carbon sheets. It is easy to manufacture, and if a double chain lock stitch is used there is no danger of the threads unraveling.

The foregoing detailed description is given for clearness of understanding only, and no unnecessary limitations should be understood therefrom, for some modifications will be obvious to those skilled in the art.

I claim:

1. A carbon pack, adapted for use between a pair of continuous-form stationery strips, comprising: a folded leader sheet, adapted to be anchored on its fold line between forwardly advancing stationery strips; a plurality of carbon sheets having their rear-end portions, with their carbonized faces upward, facing the underside of the front portion of said leader sheet and stitched thereto along a straight line, said carbon sheets being folded rearwardly about the front end of the leader sheet and their central portions folded forwardly within said folded leader sheet so that the outer carbon sheet may be completely unfolded to extended position from the leader sheet for manifolding use between the strips.

2. A carbon pack as specified in claim 1, in which the central portions of the carbon sheets are all folded together.

LESTER K. FLEISCHMANN.
